UNITED STATES PATENT OFFICE.

THOMAS H. BISHOP, OF ROCHESTER, NEW YORK, ASSIGNOR TO THE LINE-A-TIME MFG. CO., INC., OF ROCHESTER, NEW YORK, A CORPORATION OF NEW YORK.

BOOK-HOLDING COPYHOLDER.

Application filed October 16, 1920. Serial No. 417,374.

To all whom it may concern:

Be it known that I, THOMAS H. BISHOP, of Rochester, in the county of Monroe and State of New York, have invented certain new and useful Improvements in Book-Holding Copyholders; and I do hereby declare the following to be a full, clear, and exact description of the same, reference being had to the accompanying drawings, 10 forming a part of this specification, and to the reference numerals marked thereon.

My present invention relates to copyholders and more particularly to that type of copyholder adapted to be used in connection with and to stand in rear of a typewriter and embodying an upright frame carrying a copy plate and a line indicator movable relatively to each other to progressively indicate the lines of the copy and the invention has for its object to provide a copyholder of this character fitted to accommodate heavy books and to indicate the printed lines thereof, the improvements being directed in part toward rendering such device simple, durable and convenient to operate. A further object of the invention is to provide an improved clutch mechanism for raising the copy plate relatively to the line indicator, this being necessitated by the weight of the book. To these and other ends the invention resides in certain improvements and combinations of parts all as will be hereinafter more fully described, the novel features being pointed out in the claims at the end of the specification.

In the drawings:

Figure 1 is a front view of a bookholding copyholder constructed in accordance with and illustrating one embodiment of my invention;

Figure 2 is a rear view thereof;

Figure 3 is a top view;

Figure 4 is a side view;

Figure 5 is a vertical central section taken from front to rear of the machine;

Figure 6 is a horizontal section on the line 6—6 of Figure 5.

Figure 7 is a front view of a clutch mechanism and a fragment of the frame with the copy plate removed, and

Figure 8 is an enlarged detail view illustrating in section on the line 8—8 of Figure 2, an adjustable stop for the elevating mechanism.

Similar reference numerals throughout the several views indicate the same parts.

Referring first more particularly to Figures 1, 2 and 4, the copyholder shown is of a familiar general type embodying an upright reenforced stamped metal frame 1 adapted to stand at the rear of the typewriter and supported by a side arm 2 connected to its bottom rail 3. A forwardly and rearwardly extending operating lever 4 pivoted at 5 to the side arm is connected at its rear end at 6 to a transversely extending actuating lever 7 pivoted at 8 on the interior of the frame 1. A spring 9 shown in dotted lines in Figure 1, tends to hold the lever 7 in a lowered position and hence the handle portion of the operating lever 4 in an elevated position. Depressing this handle portion raises the actuating lever 7 and with it a clutch rod 10 pivotally connected thereto at 11, also as shown in dotted lines in Figure 1.

The upper end of this clutch rod 10 is shown in Figure 7, together with a portion of a lifting rod 12 guided in frame 1 and fixed as by the nut 13 shown in Figure 2 to a copy plate 14 movable vertically on guide rods 15 fixed in the frame. Referring now principally to Figure 7, the lifting rod 12 is surrounded by a tilting friction lifting clutch 16 having interlocked therewith a pair of notched friction shoes 17 engaging on opposite sides of the rod and at the other end the clutch embraces the clutch rod 10 which has a fulcrum pin 18 on which the clutch plate rests loosely. At each actuation of the operating lever 4 whereby the clutch rod 10 is raised as before explained, the clutch 16 binds upon the rod 12 and raises the copy plate to which it is attached, a corresponding distance, the bent-over end 19 of the clutch rod preventing the clutch from binding in an upward direction. When so raised, the copy plate is retained in elevated position during the return downward movement of the clutch 16 and rod 10 by a clutch plate 20 fulcrumed at 21 on an ear struck from the sheet material of the frame 1 and similarly provided with friction shoes 22 engaging the rod 12. A coil spring 23 connected to the ear 21 and to an intermediate portion of such clutch tilts the latter downwardly toward its gripping position. The opposite end of the clutch plate straddles

the rod 10 and lies above the fixed ear 24 shown to be stamped out of the material of the plate 1. Between the clutches 16 and 20 is a brake beam 25 also surrounding the lifting rod 12 and provided with friction shoes 26 similar to those on the clutches, the rod engaging portion being intermediate the ends of the beam. One of these ends rests lightly on the free end of the holding clutch 20 with which it has an adjustable contact in the present form of a set screw 27. Its other end is slotted at 28 and rests on a yoke 29 carried by a collar 30 on a tension rod 31 longitudinally adjustable in a bracket 32 by means of a nut 33 threaded on the rod and bearing against the top of the frame 1. A spring 34 acting against a washer 35 on the lower end of the rod tends to draw it downwardly subject to the adjustment of the nut 33. A spring 36 interposed between beam 25 and the upper bracket arm 32 holds the beam upon the yoke 29 and disposed at such an angle with reference to the lifting rod 12 as will normally permit the rod to slip through the brake with little or no resistance therefrom.

The copy plate falls or is returned by gravity when the clutches 16 and 20 are released. This is caused by lifting up on the operating lever 4 which reverses the movement of the clutch rod 10 causing it to move downwardly. This trips the lifting clutch 16 by straightening it out on top of the frame 1. Also, a pin 37 on the clutch rod depresses the right hand end of the brake beam 25 causing it to tighten at 26 against the lifting rod 12 immediately or with a delayed action, according to the initial angle of the beam as adjusted by the nut 33. Therefore the strength of the lifting pressure on the operating lever 4 determines the extent to which the brake will be applied.

As the brake beam is depressed in this manner, it straightens out and releases the holding clutch 20 due to the pressure of the set screw 27 on the free end of clutch 20 which is pressed down against the ear 24 and its inoperative position thereby determined.

The copy plate is thus raised to indicate successive lines of the copy with a step-by-step motion, the indication being made by a line indicator 38 carried on a bail 39 having bearings in the frame at 40 (see Figure 7). The line indicator may be adjusted in its bearings up and down in front of the copy plate and toward and from it to a limited extent, but otherwise the copyholder 60 operates upon the principle of a fixed line indicator and movable copy plate. The extent to which the copy plate is lifted upon each depression of the operating lever 4 is limited by the device shown in detail in Figure 8. The lower end of the clutch rod 10,

after passing through its bearing 11 in the actuating lever 7, is turned upwardly at 12 below a shoulder 40 on a plate 41 slotted at 42 and held against the back of the frame 1. A threaded bolt 43 extending through the back plate 1 of the frame also extends through the slot 42 and engages a nut 44 held against turning by a flange plate 45 clamped between the plate 41 and its support. By loosening and tightening this bolt 43 through the use of a knurled head 46 thereon projecting at the back of the machine as shown in Figure 2, the shoulder 40 may be adjusted to allow greater or less throw of the clutch rod 10.

The clutch mechanism above described, together with the brake acting in conjunction therewith, provides a strong and serviceable elevating mechanism for copy so heavy as a book and one which insures a gradual and noiseless descent of the copy plate when released. The book is held upon the copy plate in the following manner:

Referring more particularly to Figures 1 and 5, I provide centrally on the copy plate near its bottom a raised slotted guide 47 in which is secured for vertical adjustment by a bolt 48 and thumb nut 49 a slide 50 carrying a horizontally or forwardly and outwardly projecting standard 51. In a similar position at the top of the copy plate I provide a vertically adjustable slide 52 slotted at 53 to guide upon headed pins 54. Another pin 55 on the slide occupies a segmental cam slot 56 in a lever pivoted at 57 to a plate 58 that carries the slide which lever has an operating handle 59. By means of this member 59 the slide 52 may be raised and lowered (it being in its low position in Figure 1) for which purpose the cam provides a very fine or sensitive adjustment. It will be noted that the lower slide 50 and standard 51 has a similar though coarser adjustment and one of greater extent.

Pivoted at 60 upon each of the standards 61 carried by the upper slide 52 and 51 carried by the lower slide are a pair of equalizing beams 62 and at their opposite ends these beams are pivoted at 63 to a pair of clips 64 consisting of metal plates having downwardly turned hooks 65 at their upper ends and upwardly turned hooks 66 at their lower ends. Each clip or plate is extensible being made in two parts that slide upon each other, one being slotted as shown in dotted lines at 67 in Figure 1, and the other being provided with a headed pin 68 slidable in the slot, together with centering projections 69 struck up from the plate. Thus, the clips are extended and contracted as the slides 50 and 52 are moved toward and from each other. The lower standard 51, in addition to the beam 62 has pivoted to it at 70 (Figure 6) a link 71 connecting the clips 64 to which it is pivoted at 72 for

parallel movement in which they maintain themselves parallel with the face of the copy plate.

An open book to be copied is applied to the holder in the manner shown in Figure 1, the hooks 65 and 66 of the clips 64 being engaged over the top and bottom edges of each cover and because of the pivoted mounting of the clips, they respectively advance or recede from the face of the copy plate to bring both pages in the same plane whether the book is opened in the middle or elsewhere. To adjust the holding devices for the reception of the book, the lower standard 51 and slide 50 are first adjusted to bring the hooks 65 and 66 of the clips substantially the proper distance apart to admit the book with the slide 52 at the top raised. The lever 59 is then moved to the position of Figure 1 carrying the upper slide 52 downwardly and clamping the upper hooks 65 against the cover edges, the lower edges of the covers having been preliminarily rested in the hooks 66.

The line indicator 38, is, of course, disposed across the face of the book as shown in Figure 1, with the book between it and the copy plate. It is desirable to provide means for holding the leaves of the book flat to keep them free of the line indicator and for this purpose I have disposed transversely across the face of the copy plate between the upper and lower clip carrying guides, a reenforcing plate 73 carrying headed pins 74 upon which are guided slide bars 75. Pivoted at 76 at the center of the plate 73 is a lever 77 having pivots 78 at its upper and lower ends by means of which links 79 connected through other pivots 80 with the slide bars 75 so that these have joint outward and inward movement at the respective sides of the copy plate. At their outer ends the slide bars 75 have pivoted thereto at 81 forwardly extending arms 82 to the forward ends of which are pivoted at 83 inwardly turned arms 84 carrying fingers 85 tipped with rubber at 86 to engage the margins of the leaves of the book. The adjustments of the slides 75 are to take care of books of different widths and the arms 84 are normally pressed inwardly to cause the fingers 85 to grip the face of the book by springs 87, connected to the arms 84 at one side of their pivot and carried by the arms 82. The spring is so arranged that the arms 84 may be swung out to clear the book in adjusting it in place until such arms 84 are practically in continuation of the arms 82, the pull on the springs 87 being then on a dead center with respect to the pivots 83.

With a bookholder of the character described, legal and similar heavy books can be securely arranged on the copyholder and raised and lowered with certainty and without noise. To turn the pages, it is only

necessary to manipulate the finger 85, as the book is held by its covers and not by its pages.

I claim as my invention:

1. In a bookholding copyholder, the combination with a frame, a copyplate and a line indicator thereon and means for operating one of said elements relatively to the other, of a pair of standards on the copy plate, a pair of bookholding clips arranged between the line indicator and plate and equalizing beams supporting the clips and mounted on the standards.

2. In a bookholding copyholder, the combination with a frame, a copyplate and a line indicator thereon and means for operating one of said elements relatively to the other, of a pair of standards on the copy plate, a pair of extensible book holding clips arranged between the line indicator and plate, equalizing beams supporting the clips and mounted on the standards, and means for adjusting the latter relatively in a direction longitudinally of the clips.

3. In a bookholding copyholder, the combination with a frame, a copyplate and a line indicator thereon and means for operating one of said elements relatively to the other, of a pair of standards on the copy plate, a pair of extensible book holding clips arranged between the line indicator and plate, equalizing beams supporting the clips and mounted on the standards, and means for adjusting the latter relatively in a direction longitudinally of the clips, comprising a slide upon which one of the standards is carried and a cam lever pivoted to the plate and cooperating with the slide.

4. In a bookholding copyholder, the combination with a frame, a copyplate and a line indicator thereon and means for operating one of said elements relatively to the other, of a pair of standards on the copy plate, a pair of extensible book holding clips arranged between the line indicator and plate, equalizing beams supporting the clips and mounted on the standards, and means for adjusting the latter relatively in a direction longitudinally of the clips, comprising slides upon which the standards are respectively carried, one of said slides having a coarse adjustment embodying a releasable clamping means and the other a fine adjustment embodying a cam lever pivoted to the plate and cooperating with such slide.

5. In a bookholding copyholder, the combination with a frame, a copyplate and a line indicator thereon, and means for operating one of said elements relatively to the other, of a pair of standards on the copy plate, a pair of bookholding clips arranged between the line indicator and plate and supported on the standards, guides on the plate beneath the clips extending trans-

versely thereof, and spring actuated leaf holders operating in the guides and connected for joint movement.

6. In a bookholding copyholder, the combination with a frame, a copyplate and a line indicator thereon, and means for operating one of said elements relatively to the other, of a pair of standards on the copy plate, a pair of book holding clips arranged between the line indicator and plate and supported on the standards, guides on the plate beneath the clips extending transversely thereof, slides operating in the guides, a link mechanism connecting the slides for joint movement in opposite directions and spring actuated leaf holding arms carried by the slides.

7. In a copyholder, the combination with

an upright supporting frame, and a copyplate movable thereon and provided with a lifting rod, of elevating mechanism comprising a tilting friction clutch plate embracing the rod and separate friction shoes interlocked with the clutch plate and frictionally engaging opposite sides of the rod. 25

8. In a copyholder, the combination with an upright supporting frame, and a copyplate movable thereon and provided with a lifting rod, of elevating mechanism embodying a lifting clutch and a holding clutch, a clutch rod carrying the lifting clutch and a brake mechanism operated by a reversal of the clutch rod and through the medium of which brake mechanism the holding clutch is released by such reversal. 30

THOMAS H. BISHOP.
